G. KELLER,
TENSION DEVICE FOR WARP BEAMS,
APPLICATION FILED JAN. 29, 1913. RENEWED AUG. 3, 1915.
1,180,045.

Patented Apr. 18, 1916.

UNITED STATES PATENT OFFICE.

GOTTLIEB KELLER, OF NEW YORK, N. Y.

TENSION DEVICE FOR WARP-BEAMS.

1,180,045.

Specification of Letters Patent. Patented Apr. 18, 1916.

Application filed January 29, 1913, Serial No. 744,858. Renewed August 3, 1915. Serial No. 43,472.

To all whom it may concern:

Be it known that I, GOTTLIEB KELLER, a citizen of the Republic of Switzerland, and a resident of the city of New York, borough 5 of Manhattan, in the county and State of New York, have invented a new and Improved Tension Device for Warp-Beams, of which the following is a full, clear, and exact description.

10 The object of the present invention is to provide a new and improved tension device for warp beams arranged to permit of conveniently and accurately adjusting the device to any desired degree according to the 15 tension desired on the warp and to enable the operator to quickly throw off the tension on the warp beam whenever it is desired to release the warp for any reason whatever.

In order to accomplish the desired result, 20 use is made of a band winding around the warp beam, an adjustable tension device connected with one end of the said band, and manually-controlled means connected with the said adjustable tension device for 25 throwing the latter off to release the band and to hold the tension device in the thrown off position.

A practical embodiment of the invention 30 is represented in the accompanying drawings forming a part of this specification, in which similar characters of reference indicate corresponding parts in all the views.

Figure 1 is an end elevation of a loom 35 showing a warp beam having the tension device attached thereto; Fig. 2 is an enlarged sectional side elevation of the tension device as applied; Fig. 3 is a similar view 40 of the same and showing the parts in different positions; and Fig. 4 is a sectional plan view of the same on the line 4-4 of Fig. 2.

The frame A of the loom is provided with 45 bearings for the shaft B carrying a warp beam C from which unwind warp threads D, and on the ends of the warp beam C are secured pulleys E, around each of which is wound several times a braided band F terminating at one end in a hook F' hooked onto a staple G driven into the 50 floor or other support (see Fig. 3). The other end of each band F terminates in a loop F² formed by doubling up the end of the band and engaging the doubled-up portion by an adjustable clip H having a casing H', a clamping bar H² within the casing, and a set screw H³ pressing the clamping

bar H² against the band so as to securely fasten the doubled-up portions of the band together, thereby providing a loop F² which can be adjusted by shifting the clip 60 H of the band.

The loop F² of the band F connects with a tension device adapted to be set to provide any desired degree of tension for the warp threads D, as hereinafter more fully explained. The loop F² engages a pin I' held 65 on a head I² attached to and forming part of a rod I mounted to slide up and down in the top J' of a stand J provided with a foot J² secured by bolts K' to a base plate 70 K bolted or otherwise fastened to the floor.

The bolts K' engage transversely-extending slots K² formed in the base plate K to allow of adjusting the stand J in a transverse direction to locate the stand in alignment with the pulley E on the warp beam shaft B (see Fig. 1). Thus for longer or shorter warp beams the stands J can be 75 readily adjusted on the base plates K to extend in alignment with the pulleys E. 80

The lower end I³ of the rod I is provided with screw threads on which screws a nut I⁴ against the under side of a plate L mounted to slide up and down on the stand J. The threaded end I³ of the rod I 85 passes loosely through the plate L and the latter is provided with a pointer L' extending through a vertical slot J³ formed in the stand J, the pointer L' indicating on the graduation O arranged on the face of 90

the stand J. The plate L is provided with friction rollers L² in contact with the front and rear of the stand J so as to allow an easy up and down sliding movement of the plate L on the stand J. The end of the plate 95 L is provided with lugs L³ carrying a pin L⁴ to which the loop F² of the band F may be attached in case the warp beam C is located closer to the floor. A spring N is coiled around the rod I and abuts with its 100

upper end against the under side of the top J', and the lower end of the spring N rests on the plate L so that the latter is under tension. The upper end of the rod I is provided with a vertical slot I⁵ through 105 which extends the transverse pivot pin P' of a cam lever P having its cam face P² resting on the top J' of the stand J. It will be noticed that by screwing the nut I⁴ up or down on the threaded end I³ of the 110 rod I more or less tension can be given to the spring N, the amount of tension being

preferably indicated in pounds by the graduation O, as shown in Fig. 1.

- The operation is as follows: The warp threads D are unwound from the warp beam C in a series of short advances and not continually. The initial friction between the bands F and the pulleys E is greater than the tension of the spring N and thus at each advance of the warp threads D the bands F turn for a short distance with the pulleys E and the warp beam C until the tension of the spring N becomes greater than the friction whereupon the springs pull down on the loop F² of the band F to return the latter to normal position, of course, always maintaining the warp threads D under the proper tension and at no time permitting the same to become slack. When it is desired to release the bands F of the tension device then the operator swings the cam levers P from the normal vertical position downward into a horizontal position, as indicated in dotted lines in Fig. 2, whereby the pivot pin P' lifts the rod I against the tension of the spring N, and in doing so the tension on the loop F² is released to allow the lever to turn the warp beam C for slackening the warp whenever it is desired to do so for any reason whatever. When it is desired to again place the warp threads D under the proper tension the operator swings the cam levers P upwardly back into vertical position thus allowing the springs N to push the rods I downward so that the loops F² of the bands F are placed again under the tension to which the tension device was originally set by the operator adjusting the nut I⁴, as before explained. Each band F is preferably made of braided cords thus providing exceedingly strong and durable bands which can be readily wound around the pulleys E and provide the desired frictional contact between the bands and the pulleys at the same time reducing the wear of the bands and pulleys to a minimum and insuring long life to the tension device.
- Having thus described my invention, I claim as new and desire to secure by Letters Patent:

1. In a loom, the combination with a warp beam, of a band wound around the said warp beam, a stand having a guideway, a spring-pressed rod mounted to slide on the said

stand and having a slotted upper end, one end of the said band being connected with the said rod, and a cam lever having its pivot engaging the slotted upper end of the said rod and the said guideway, the cam face of the said cam lever having a bearing on the said stand.

2. In a loom, the combination with a warp beam of a band wound around the said warp beam, a stand having a guideway, a spring-pressed rod mounted to slide on the said stand and having a slotted upper end, one end of the said band being connected with the said rod, the lower end of the said rod being threaded, a nut screwing on the said lower threaded end, a plate loosely engaging the said rod and resting on the said nut, the plate slidably engaging the said stand, a spring coiled on the said rod and abutting with its upper end on the said stand, the lower end of the said spring resting on the said platform, and a cam lever having its pivot engaging the slotted upper end of the said rod and the said guideway, the cam face of the said cam lever having a bearing on the said stand.

3. In a loom, the combination with a warp beam of a band wound around the said warp beam, a stand having a guideway, a spring-pressed rod mounted to slide on the said stand and having a slotted upper end, one end of the said band being connected with the said rod, the lower end of the said rod being threaded, a nut screwing on the said lower threaded end, a plate loosely engaging the said rod and resting on the said nut, the plate slidably engaging the said stand, a spring coiled on the said rod and abutting with its upper end on the said stand, the lower end of the said spring resting on the said platform, a cam lever having its pivot engaging the slotted upper end of the said rod and the said guideway, the cam face of the said cam lever having a bearing on the said stand, a graduation on the said stand, and a pointer on the said plate indicating on the said graduation.

In testimony whereof I have signed my name to this specification in the presence of two subscribing witnesses.

GOTTLIEB KELLER.
